COMBINED SCRAPER AND BRUSH FOR ALUMINUM SASH AND FRAMES OR THE LIKE

Robert A. Geddes, 533 Patton Ave., San Jose, Calif.

Filed Feb. 18, 1963, Ser. No. 73,609

Term of patent 3½ years

(Cl. D9—6)

FIG. 1 is a perspective view of a combined scraper and brush for aluminum sash and frames, the dotted line disclosure of which is for the purpose only of illustration.

FIG. 2 is a side elevational view thereof.

FIG. 3 is a top plan view thereof.

FIG. 4 is a bottom view thereof.

FIG. 5 is an end view as seen from the left in FIG. 2.

FIG. 6 is an end view as seen from the right in FIG. 2.

FIG. 7 is an end view looking directly down the handle end and as seen from line 7—7 in FIG. 2.

I claim:

The ornamental design for a combined scraper and brush for aluminum sash and frames or the like, as shown and described.
